UNITED STATES PATENT OFFICE.

THOMAS G. HITT, OF SEATTLE, WASHINGTON.

FIRECRACKER AND PROCESS OF MAKING THE SAME.

Application filed January 14, 1926. Serial No. 81,135.

This invention relates to improvements in the formation of fire crackers and in the process of making the same.

One of the objects of this invention, is to provide a fire cracker entirely devoid of end plugs and the like, the explosive matter being held within a tubular container, with both ends thereof folded back upon itself and on opposite sides thereof, and a single fuse 5 bent in the form of long loop with the two ends of the fuse embedded within the explosive within the container and the loop of the fuse extending out and beyond the container and beyond the shell in which the 10 container is placed; and the tubular container after the ends have been folded back upon the central portion to be bent longitudinally to form a groove the entire length of the folded container, so that the edges of 15 the groove will be pressed towards each other sufficiently to permit the entire container to be readily inserted in a suitable shell, and then the edges of the groove to expand and impinge against the inner periphery of the 20 shell and securely hold the container in any determined position with the shell.

Further objects of this invention will appear from the disclosure in the single sheet of drawings herewith made a part of this 25 application, and in the following description.

In the several perspective views shown by the drawings:

Figure 1 represents the tubular container, 30 with one end bent back against the middle section thereof, with the explosive being poured into the other open end;

Fig. 2, illustrates a vertical sectional view of the container with a charge of explosive 35 in the central section thereof, with one end of the container bent back and flattened against the said central section, and a long fuse member in the form of a loop, with the two ends thereof embedded within the explosive and the loop portion extending out 40 from the tube.

Figure 3 represents the container with both ends bent back on opposite sides of the central section, and the three parts bent 45 longitudinally to form a groove on one side thereof;

Figure 4 represents the container inserted within a larger and tubular fire cracker shell, in completed condition.

Like numerals on the different figures represent like parts.

1 is the outer shell, preferably formed in straight tubular form of thin cardboard with the openings of same diameter at each end to permit the ready insertion therein 50 of the explosive container. 2 is a tubular container for the explosive, of smaller diameter than the shell, and preferably formed of heavy paper with some resilient quality, into which is inserted a fuse 3 in form of a 55 loop, with the two ends thereof 4 and 5 embedded within a charge of explosive 6, and 6^a represents a supply of explosive being poured into the open end of the container. Before supplying the explosive, the lower 70 end portion and approximately one third of the container is bent back at point 7 and flattened as 8 against the middle section or pocket 9, thus closing the tube 2 at the bend to prevent the escape of the explosive, and 75 the upturned end 8 also forms an additional sheath over the explosive and causes a loud report when the explosion occurs. The other open end of the tube provides facility for admitting the charge of explosive. 80

When a proper supply of explosive has been placed in the central portion or pocket 9 of the container, the two ends of the fuse are inserted in the explosive at opposite sides within the container, thus insuring 85 greater certainty of igniting the charge when the loop end is fired, and the upper section 11 of the tube is then bent back at approximately the line 10, and over the pocket 9 on the opposite side from the end 8, for the purpose of closing the tube and preventing the loss of explosive, and to provide additional material to be burst when the explosion takes place. The two lines of 90 fuse being at opposite sides and against the wall of the tube will not be so tightly bound by the bent tube as they would be if centrally placed, as the folded edges tend to form spaces for the fuse, and this prevents the tendency of the fire in the fuse being 95 extinguished at the bend, as is frequently the case where the explosive containers are tied, etc. or twisted as in ordinary methods of fastening explosive containers for fire crackers. 100

The two edges 12 and 13 of the section 11 and the corresponding edges of the sections 8 and 9 are then bent longitudinally one behind the other thus forming a groove 14 the length of the sections, and as these edges are compressed towards each other and the groove narrowed, the outside circumference 105 110

of the folded container will be sufficiently reduced to be readily inserted into either end of the tubular holding shell 1 to the position desired therein. The resiliency of the compressed portions of the container when placed in the shell causes the edges 12 and 13 and the curved end 8 to expand and impinge sufficiently against the inner periphery of the shell 1, to securely hold the container in any desired position within the shell to which it has been placed, without the use of cement or other usual means.

Having described my invention, what I claim as new is;

- 15 1. A tubular container for explosive for fire crackers, with each end of the tube bent back and flattened against the central portion thereof, with a fuse extending from a charge of explosive in the container out beyond the container end, and both end portions and the central portion of the container bent longitudinally along one side to form a concave surface on that side with the bent edges of the portions expanded to an outer shell for holding the container within the shell.
- 20 2. A fire cracker with an outer tubular shell, and a charge of explosive matter within a tubular container, with a fuse bent in

form of loop with the loop portion extending beyond the shell and the two ends of the fuse embedded within the explosive and the two sides of the fuse loop lying within the container at opposite sides thereof, with both ends of the container bent back against the central portion thereof and on opposite sides thereof for holding the explosive in the central portion and to cause a loud report, and the edges of the bent portions pressed toward each other to form a groove longitudinally between the same, and the edges to bind against the inner periphery of the shell for holding the container in place.

3. The process of forming a fire cracker by placing a charge of explosive in a flexible tubular container, with a fuse extending from the charge out from one end of the container, and folding both ends of the container back over the central portion containing the charge, and bending the edges of the central and folded portions of the container toward each other on one side to form a groove longitudinally with the edges forming resilient expansive means for holding the container with a tubular shell, which is placed over the explosive container.

In testimony whereof I affix my signature.
THOMAS G. HITT.
